UNITED STATES PATENT OFFICE.

STANLEY ORZHOVSKI, OF DE KALB, ILLINOIS, ASSIGNOR TO KOHLER DIE AND SPECIALTY CO., OF DE KALB, ILLINOIS, A CORPORATION OF ILLINOIS.

CARD RACK.

Application filed May 18, 1922. Serial No. 561,857.

To all whom it may concern:

Be it known that I, STANLEY ORZHOVSKI, a citizen of the United States, residing at De Kalb, in the county of De Kalb and State of Illinois, have invented certain new and useful Improvements in Card Racks, of which the following is a specification.

The present invention relates in general to card-filing devices, and is concerned particularly with devices of this class wherein the filed data cards are held—partially visible for ready reference or removal—in the pockets of a rack.

The main and primary object of the invention resides in the provision, in such a card rack, of an improved pocket and frame construction which is of a built-up character for ready assemblage in any size, and which is featured by the combined advantages of decided reductions in weight, in amount of materials used, and in costs of production and assemblage over the ordinary form of rack wherein double-walled pockets and supporting backs for the pocket-forming members are employed.

Another important object of the invention resides in the provision of a rack of this character which dispenses with the ordinary backing member and provides pockets on both sides of the rack by using only the number of pocket-forming members usually required for one side.

While the foregoing statements are indicative of the nature of the invention, other objects and advantages not herein specifically referred to will be obvious upon a full understanding of the rack structure as set forth in the following detailed description and accompanying drawings wherein is delineated two embodiments of the invention. These particular embodiments are chosen principally for the purpose of exemplification, and are accordingly not intended to restrict the spirit of the invention or to limit unnecessarily the scope of the appended claims.

In the drawings,

Fig. 1 is a front view of the rack;

Fig. 2 is a vertical section on the line 2—2 of Fig. 1;

Fig. 3 is a horizontal section on the line 3—3 of Fig. 1;

Fig. 4 is a perspective view of one of the double pocket-forming members; and

Fig. 5 is a vertical section through a modified form of the rack wherein a backing member and a series of the single pocket-forming members are employed.

Referring now to the drawings, the rack 10 of this invention is shown as consisting of a plurality of superposed pocket-forming members 11 retained within a skeleton frame 12. This frame is constructed of two channeled uprights 13 which are connected at their tops by a channeled cap plate 14, and at their bottoms by a channeled base plate 15. The frame parts above described may be secured together by means of two tie-bolts 16. Apertured ears 17 may be provided, as shown, on the cap and base plates 70 to permit a pivotal connection of the rack with a supporting standard of that type usually employed.

The pocket-forming members 11 referred to are cut preferably from sheet metal, and bent into the shape illustrated in Figs. 2 and 4. When thus formed, these members are of approximately V-shaped cross-section and are each characterized by two symmetrically arranged side portions 18 which constitute 80 the division walls between the pockets of the rack. These side portions 18 are integrally connected at their bottoms 19, and are bent outwardly a short distance at their top edges 20 to provide, when the members are 85 assembled in the frame, a slightly diverging opening to each of the pockets formed by the members. It is desirable to have the edges 20 flush with the two faces of the frame as defined by the faces of the channeled uprights 13, and to accomplish this 90 the ends of the edges 20 are cut away at 21 to clear the uprights 13. Each of the members 11 is provided, at its ends and a short distance above its bottom, with inwardly 95 bent lips 22 which form curved seats 23 and lateral spacing abutments 24 for supporting and positioning in proper relation thereto the bottom and side portions of the member located next thereabove.

In assembling the rack the members 11 are arranged in interfitting relation with the bottoms 19 of each seated on the lips 22 of the member located next therebelow. The

ends if the stacked members are then inserted within the retaining channels of the uprights 13, and the cap and base plates attached. A corrugated strip 25 may be placed within the channel of the base plate 15, as shown in Fig. 2, for the purpose of properly positioning the lowermost pocket-forming member. When thus assembled within the frame the members 11 are prevented from disassociation, and serve to provide pockets on both faces of the rack having slightly resilient single division walls adapted to exert a holding friction on the contents of the pockets while accommodating, in each pocket, one or a plurality of data cards with equal facility.

In those racks intended for pivotal mounting on a standard, the cap and base plates may be provided, on the ends thereof opposite to the apertured ears 17, with guard members 26 adapted to serve as spacing projections or buffers between the racks when the same are swung into contact with each other.

25 In Fig. 5 is shown a modified form of the rack of this invention wherein a single-face rack is presented by the employment of a frame equipped with a backing member 27 and retaining strips 28 spaced forwardly 30 from the said backing member. The pocket-forming members 29 are positioned in the frame between the strips and backing member, and are each formed to correspond in shape to one of the halves of the previously 35 described pocket-forming members 11 were the same separated by cutting along the curved bottoms 19 thereof. The members 29 are arranged in the frame in the same interfitting relation as the members 11, the 40 lips 30 with their seats 31 and lateral spacing abutments 32 on each member serving to support and to properly position the member located next thereabove.

I claim:

45 1. In a card-holding rack, a frame, a plurality of superposed pocket-forming members arranged therein, and means carried by each of the members for engaging with the lower portion of the member located next thereabove and forming the support of the same.

50 2. In a card-holding rack, a frame, a plurality of superposed pocket-forming members removably arranged therein, and means carried by each of the members for engaging with the lower portion of the member located next thereabove and forming the support of the same.

55 3. In a card-holding rack, a frame, a plurality of superposed pocket-forming members arranged therein, and means carried by each of the members below the exposed pocket edge of the same for engaging with the lower portion of the member located next

thereabove and forming the support of the same.

4. In a card-holding rack, a frame, a plurality of superposed members arranged therein to form pockets separated by single division walls, and means carried by each of the members for forming the support of the member located next thereabove.

5. In a card-holding rack, a frame, a plurality of superposed members arranged therein to form pockets having closed bottoms and separated by single division walls, and means carried by each of the members for forming the support of the member located next thereabove.

6. In a card-holding rack, a frame, and a plurality of superposed pocket-forming members arranged therein, each of said members being formed from a sheet of stiff material and characterized by an inwardly bent portion to form the pocket bottom and spaced inwardly bent lips terminating above said bottom to form the supporting means of the member located next thereabove.

7. In a card-holding rack, a frame, a plurality of superposed members arranged therein to form pockets on both sides of the frame, and means carried by each of the members for engaging with the lower portion of the member located next thereabove, and forming the support of the same.

8. In a card-holding rack, a frame, a plurality of superposed members of substantially V-shaped cross-section removably arranged therein in interfitting relation to form pockets on both sides of the frame, and means carried by each of the members for forming the support of the member located next thereabove.

9. In a card-holding rack, a frame, a plurality of superposed members arranged therein to form pockets on both sides of the frame, and means carried by each of the members for positioning in spaced double pocket-forming relation thereto, the member located next thereabove.

10 10. In a card-holding rack, a frame, and a plurality of superposed members arranged therein to form pockets on both sides of the frame, each of said members engaging with the lower portion of the member located next thereabove and forming the sole vertical support of the same.

11 11. In a card-holding rack, a sheet metal skeleton frame consisting of two spaced inwardly opening channelled uprights, a downwardly opening cap plate, and an upwardly opening base plate; and a plurality of superposed members of substantially V-shaped cross-section arranged therein in interfitting relation to form pockets on both sides of the frame.

12 12. In a card-holding rack, a sheet metal skeleton frame consisting of two spaced in-

wardly opening channeled uprights, a downwardly opening cap plate, and an upwardly opening base plate; a plurality of superposed members arranged therein in interfitting relation to form pockets on both sides of the frame; and means carried by each of the members for forming the support of the member located next thereabove.

13. In a card-holding rack, a frame adapted for pivotal mounting at one side to swing with other frames on a common standard, the free side of the rack provided with lateral projections to serve as buffers in the swinging of the frame.

14. A card rack assembly unit comprising a substantially V-shaped body of sheet material having open ends bridged by lips angularly bent from the side walls.

15. A card rack assembly unit comprising a substantially V-shaped body of sheet material with outwardly diverging side walls marginally flared and having open ends bridged by lips angularly bent from said walls.

In testimony whereof I have hereunto subscribed my name.

STANLEY ORZCHOVSKI.
